UNITED STATES PATENT OFFICE.

LEO HASEL, OF LAKEVIEW, OREGON.

DESIGN FOR A REINFORCING-PLATE FOR SHOES.

50,573.

Specification for Design.

Patented Apr. 10, 1917.

Application filed October 9, 1916. Serial No. 124,733. Term of patent 14 years.

To all whom it may concern:

Be it known that I, LEO HASEL, a citizen of the United States, residing at Lakeview, in the county of Lake and State of Oregon, have invented a new, original, and ornamental Design for Reinforcing-Plates for Shoes, of which the following is a specification, reference being had to the accompanying drawing, forming part thereof.

The figure is a top plan view of a re-

inforcing plate for shoes showing my new design.

I claim:

The ornamental design for reinforcing plate for shoes, as shown.

LEO HASEL.

Witnesses:

F. M. MILLER,
E. H. CLARK.
